UNITED STATES PATENT OFFICE.

PAUL BECKER, OF CLEVELAND, OHIO, ASSIGNOR TO MAX M. KOCH, OF CLEVELAND, OHIO.

STOVE LID OR COVER.

1,104,163.

Specification of Letters Patent.

Patented July 21, 1914.

Application filed May 8, 1913. Serial No. 766,337.

To all whom it may concern:

Be it known that I, PAUL BECKER, citizen of the United States, residing at Cleveland, in the county of Cuyahoga and State 5 of Ohio, have invented new and useful Improvements in Stove Lids or Covers, of which the following is a specification.

My present invention pertains to stove lids or covers; and it contemplates the 10 vision of a stove lid or cover which is designed and adapted to be used to advantage in a combination range—*i. e.*, a range constructed to burn either coal or gas, and is also adapted to be used advantageously in 15 combination with a gas burner, a hydro-carbon burner or any other analogous burner in a stove not constructed to burn coal or other hard fuel.

The invention in all of its details will be 20 fully understood from the following description and claims when the same are read in connection with the drawings, accompanying and forming part of this specification, in which:

25 Figure 1 is a vertical diametrical section of the lid or cover constituting the best practical embodiment of my invention that I have as yet devised; the same being shown in proper relation to a stove top and a gas burner. Fig. 2 is a top plan view of the lid or cover *per se*. Fig. 3 is an inverted plan 30 of the lid or cover. Fig. 4 is a side elevation of the lid or cover.

Similar numerals of reference designate 35 corresponding parts in all of the views of the drawings.

The stove top 1 illustrated, is preferably the top of a combination range, and is provided with a conventional hole 2.

40 In the stove or range and below the hole 2 is located a gas burner 3, and occupying the hole and disposed above and around the gas burner is my novel removable lid or top which is constructed of metal or metals compatible with its purpose.

As will be readily noted by reference to the drawings, the lid or cover comprises a lower disk-like member 4, an upper disk-like member 5 superimposed on the member 4, and an annular skirt member 6. The members 4 and 5 are pivotally connected at 50 7, and both of the said members are provided with perforations 8, the said perforations being so arranged that when the upper member 5 is in one position it will close the per-

forations in the lower member 4, while when said upper member 5 is in another position its perforations will be in registration with those of the lower member 4 so as to permit of the direct passage of flames and heat 60 through the perforations of the two members 4 and 5 and to the bottom of a cooking utensil placed on the upper member 5. The upper member 5 is provided at 8^a with a large perforation designed to receive an implement through which the member is turned about its axis, and in order to limit the turning of the member 5 so as to assure its perforations being registered with those of the member 4, I provide the member 5 with a 70 curvilinear slot 9, and the member 4 with a stop projection 10, disposed in said slot 9.

In the perimeter of the lower member 4 are recesses 11, and on the upper member 5 and disposed in said recesses are lugs 12. 75 These lugs 12 depend below the lower member 4, and serve to give the lid or cover as a whole a firm seat in the hole 2. Manifestly by reason of the disposition of the lugs 12 in the recesses 11, the said lugs do not interfere with the turning of the member 5 on the member 4. It will also be manifest from the foregoing that when the lid or cover is disposed in the hole 2 and the frictional contact between the edge of the member 5 and the wall of the hole renders it difficult to turn the said member 5, the member 4 may be turned under the member 5; a suitable implement in that case being engaged with the stop projection 10 of the lower member 4. 80 85 90

Fixed with respect to and depending from the lower member 4 at points adjacent the perimeter thereof are connecting devices which are preferably in the form of hooks 95 13, as illustrated. These connecting devices or hooks 13 are designed for the engagement of connecting devices 14 on the annular skirt member 6; the said connecting devices 14 being preferably in the form of radial projections arranged on the skirt member adjacent the upper edge thereof. It will also be noted that the skirt member 6 is provided in its upper edge with notches 15, for an important purpose hereinafter described. 100 105

When the projections 14 of the skirt member 6 are disposed in the hooks 13 of the lower disk-like member 4, it will be observed that the skirt member 6 is strongly connected with the member 4 without lia- 110

bility of the skirt member 6 becoming casually disconnected from the member 4. When, however, it is desirable not to use the skirt member 6, the same can be expediently and easily disconnected from the said disk-like member 4.

When my novel lid or cover is used on a combination range, and coal or other hard fuel is consumed in the range, it is preferable not to use the skirt member 6, this in order that the draft in the flue below the hole 2 may be unobstructed. When the lid or cover is so used, the lower member 4 is adjusted after the fire is well started so as to place its perforations in registration with the perforations of the upper member 5, and permit the direct passage of heat to a utensil disposed on the member 5.

The skirt member 6 is designed especially for use when the burner 3 is employed, and in such use of the skirt member it will be manifest that it will confine the flame and heated products of combustion between the burner and the under side of the lower disk-like member 4, and will effectually prevent the draft in the flue under the stove-pipe from drawing the said flame and products of combustion toward the up-take of the stove or range. In this connection, however, it will be noticed that the notches 15 in the upper edge of the skirt member 6 form eduction openings through which consumed gases can pass to the flue under the top 1. This will be appreciated as an important advantage when it is stated that the said consumed gases would be very obnoxious were they permitted to pass into the apartment in which the stove or range is located. It will further be noted that the eduction apertures formed by the notches 15 in the skirt 6 assure the necessary draft through the burner and skirt to support combustion.

Having described my invention, what I claim and desire to secure by Letters-Patent, is:

1. A stove lid or cover comprising a lower foraminous disk-like member having recesses in its perimeter and an upstanding projection on its upper side and also having depending hooks at points adjacent its perimeter; an upper disk-like foraminous member superimposed on the lower disk-like member and having a slot receiving the projection on the lower member and also having at its perimeter lugs that depend through the recesses in the lower member and extend below said lower member; a central pivotal connection between the lower and upper disk-like members; and an annular skirt member having radial projections removably arranged in the hooks of the lower disk-like member and also having

notches in its upper edge constituting eduction apertures.

2. A stove lid or cover comprising a lower foraminous disk-like member having recesses in its perimeter, and an upper disk-like foraminous member to which the lower member is pivotally connected; said upper member having at its perimeter depending lugs, disposed in said recesses of the lower member.

3. In a stove lid or cover, the combination with a disk-like member having hooks adjacent its perimeter, said hooks depending from said member and having openings in the upper portions of their sides; of a skirt-member having radial projections movable through openings of the depending hooks of the disk-like member and removably seated in said hooks.

4. A stove lid or cover, comprising a lower foraminous disk-like member having recesses in its perimeter, an upper disk-like foraminous member to which the lower disk-like member is pivotally connected; said upper member having at its perimeter lugs that depend through the recesses in the lower member and extend below said lower member, and a skirt member arranged within the group of depending lugs on the upper member and connected with the lower member.

5. A stove lid or cover, comprising a lower foraminous disk-like member having recesses in its perimeter, an upper disk-like foraminous member to which said lower member is pivotally connected; said upper member having at its perimeter lugs that depend through the recesses in the lower member and extend below said lower member, depending hooks on the lower disk-like member at points adjacent the perimeter thereof, and a skirt member arranged within the group of depending lugs on the upper disk-like member and having radial projections removably arranged in the said hooks.

6. A stove lid or cover, comprising a lower foraminous disk-like member having recesses in its perimeter and also having an upstanding projection on its upper side, an upper disk-like foraminous member to which the lower disk-like member is pivotally connected; said upper member having a slot receiving the projection of the lower member and also having at its perimeter lugs that depend through the recesses in the lower member and extend below said lower member.

In testimony whereof I have hereunto set my hand in presence of two subscribing witnesses.

PAUL BECKER.
